UNITED STATES PATENT OFFICE.

HERBERT JOSEPH HASTINGS AND CHARLES ST. VINCENT SMITH, OF EAST TWICKENHAM, ENGLAND.

MECHANICAL TOY OPERATED BY GRAMOPHONES.

1,424,015.

Specification of Letters Patent. Patented July 25, 1922.

Application filed September 2, 1921. Serial No. 498,030.

To all whom it may concern:

Be it known that we, HERBERT JOSEPH HASTINGS and CHARLES St. VINCENT SMITH, both of 28 St. Stephen's Gardens, East Twickenham, England, subjects of the King of Great Britain, have invented certain new and useful Improvements in Mechanical Toys Operated by Gramophones, for which we have filed an application in England 6th 10 January, 1920, Patent No. 160951 (No. 403/20), of which the following is a specification.

This invention relates to improvements in mechanical toys of the kind comprising an upright magnetized spindle mounted to revolve in bearings, a stationary table of non-magnetic material through which the upper end of said spindle projects, an armature adapted to rest upon said table and to be moved thereover as a result of magnetic attraction between the peripheral surfaces of the spindle and armature respectively, a figure carried by said armature so as to be moved thereby in accordance with the peripheral configuration of the armature, and means for imparting rotary motion to the spindle.

The object of the present invention is to enable such a toy to be used in combination with a phonograph of the disc-record type, in such manner that rotation will be imparted to the magnetized spindle by frictional transmission from the turntable which serves to carry and rotate the phonograph-record, or, it may be, from the record itself; the invention being more particularly directed to providing a construction such that, on the one hand, the frictional transmission-device will be capable of self-adjustment to suit turntables mounted to revolve at different levels relatively to the top of the phonograph-casing whereon the toy as a whole rests, and that, on the other hand, the speed of the rotation imparted to the magnetized spindle may be regulated at will in order that the figure carried by the armature may if desired be caused to perform movements in time with musical sounds produced by the phonograph.

The invention will be described with ref-

erence to the accompanying drawings, wherein Figure 1 is an elevation, in section upon line 1-1 of Figure 2, shewing a portion of the casing of a phonograph of the disc-record type, with a portion of the turntable and of a record resting thereon, one form of the improved toy being supported upon the top of the casing. Figure 2 is a corresponding plan view. Figures 3 and 4 shew in plan view two armatures each differing in peripheral configuration from the armature illustrated in Figure 2.

The toy as illustrated in the drawings comprises a frame *a* having a weighted base *b* adapted to rest securely upon the top *c* of a gramophone-casing in a position adjacent to the usual horizontal turntable *d* which serves to carry and impart rotation to a record-disc *e*; the upper part of the frame *a* supporting a stationary horizontal table *f* of non-magnetic material such as sheet brass, whilst an upright magnetized spindle *g* is mounted to revolve in bearings in the base *b* and table *f* as indicated.

An armature *h* of magnetic material, such as thin sheet iron or steel for example, is adapted to rest upon and slide easily, with a minimum of frictional resistance, over the surface of the table and in contact with the upper end of the spindle *g* which projects a short distance above the table; the armature *h* being adapted to support a figure *j* (such for example as a pair of waltzing partners, as indicated) formed of stiff paper or other similar light material; for which purpose the armature may have, as shewn, a pair of tongues *k* stamped-up to receive and clip the lower edge of the figure *j* between them. When the edge of the armature *h* is brought into contact with the periphery of the spindle *g* it will adhere thereto by magnetic attraction, so that, upon the spindle being caused to revolve about its vertical axis, the armature will slide continuously over the table *f* with a movement whereof the direction will change continually or from time to time as determined by the peripheral configuration of the armature *h* itself; the adhesion between the armature and spindle remaining unbroken, whilst the speed at which

the armature is thus moved is dependent upon the speed of revolution, and the relative diameter, of the spindle *g*. The shapes of the individual armatures shewn in Figures 2, 3 and 4 are severally adapted to give to a figure or figures such as illustrated in Figure 1, when carried by the respective armatures, movements representing approximately those characteristic of different 10 waltz-steps; but it will be understood not only that any kind of figure may be represented, but that the peripheral configuration of the armatures employed may be varied indefinitely within the limits imposed by the necessity for the uninterrupted 15 maintenance of contact between the spindle *g* and the edge of the armature. The form of armature represented in Figure 4, for example, is adapted to give the dancing figures *j* the appearance of reversing their step at intervals.

For the purpose of transmitting rotation from the turntable *d* to the spindle *g*, the latter has fixed concentrically upon it a horizontal disc *m* whereon a disc *o* of cardboard (or other suitable non-magnetic material) is adapted to rest by gravity; the disc *o* being centrally apertured to give free passage to the spindle *g* in such manner that the disc *o* 20 can not only turn but also slide or cant relatively to the spindle. When the frame *a* is set upon the top *c* of the phonograph-casing in a suitable position adjacent to the turntable *d*, and the loose or floating disc *o* is 25 allowed to rest, towards opposite sides of the spindle *g*, upon the margin of the turntable (or, as in the example illustrated, upon the margin of the record *e*) and upon that of the fixed disc *m* respectively, then, if the 30 turntable *d* be set in motion, a continuous rotary movement will be transmitted through the floating disc *o* to the disc *m* and spindle *g*, with the result that the figures *j* carried by the armature *k* will move with the latter over the table *f* and in so doing will perform evolutions determined by the peripheral shape of the armature.

As will be observed on reference to Figure 1, the floating disc *o* is free to adjust its 35 position, if necessary by becoming canted out of the horizontal as shown, so as to maintain contact with both the turntable *d* and fixed disc *m* notwithstanding considerable variations in their relative levels; *p* 40 representing a circular washer loosely centered about the spindle *g* so as to be adapted to rest continuously upon the loose disc *o* in all positions of the latter and, by suitably loading said disc, to ensure maintenance of 45 the requisite frictional contact between it and both the turntable *d* and fixed disc *m*.

The speed of revolution imparted to the spindle *g* may be regulated by moving the frame *a*, with all the parts carried thereby, 50 towards or from the axis of revolution of

the turntable *d* so as to alter the effective length of that radius of the floating disc *o* whereat the latter contacts with and receives motion from the turntable or (as in the example illustrated) the record *e*, and thus to adjust the rate at which the evolutions of the figures *j* are performed, in accordance with the time of the music produced by the phonograph. In order to facilitate such adjustment, it is found advantageous to form the floating disc *o* with a depressed annular margin *r* so that, by approaching the frame *a* sufficiently close to the edge of the turntable *d* (or record *e*), said edge may in effect be made to contact with the underside of the disc *o* at more than a single point, a slight but variable braking-effect being thus produced which in practice is found to increase with the extent to which the disc *o* overlaps the turntable or record. 55

We claim:—

1. A mechanical toy for use in combination with a phonograph of the disc-record type, comprising a weighted frame, a stationary horizontal table of non-magnetic material carried thereby, an upright magnetized spindle mounted to revolve in bearings in said frame, the upper end of said spindle projecting through an aperture in the table, a disc fixed concentrically upon the spindle, a floating disc of non-magnetic material centrally apertured so as to give free passage to said spindle and to be adapted to rest upon the margin both of said fixed disc and also of a phonograph-turntable, an armature of magnetic material adapted to rest upon and slide easily over the surface of said table, and a figure carried by said armature, substantially as and for the purpose set forth.

2. A mechanical toy as claimed in claim 1, wherein the floating disc has a central aperture of a diameter sufficient to permit of said disc becoming canted relatively to the axis of the upright magnetized spindle so as to be adapted to transmit motion from the phonograph turntable to the disc fixed concentrically upon said spindle, when said fixed disc is at a level different from that of the turntable.

3. In a mechanical toy as claimed in claim 1, the combination with the floating disc, of a washer loosely centered about the upright magnetized spindle of the toy so as to rest by gravity upon said disc, substantially as and for the purpose set forth.

4. A mechanical toy as claimed in claim 2, wherein the floating disc is formed with a depressed annular margin, substantially as for the purpose set forth.

5. In a mechanical toy for use with a phonograph, a revoluble spindle, a toy carrying member operated by the spindle, a floating disk loosely mounted on the spindle so as to tilt and adapted to engage the turntable of

a phonograph, and means on the spindle and cooperating with the tilted disk to rotate the spindle.

6. In a mechanical toy for use with a phonograph, a revoluble spindle, a toy carrying member operated by the spindle, a disk fixedly secured to the spindle, and a floating

disk loosely and tiltingly mounted on the spindle and adapted to engage the phonograph turntable and the fixed disk when in a 10 tilted position.
